UNITED STATES PATENT OFFICE

WILLIAM A. DOBSON, OF BRIDGEPORT, CONNECTICUT, ASSIGNOR TO UNDERWOOD ELLIOTT FISHER COMPANY, OF NEW YORK, N. Y., A CORPORATION OF DELAWARE

TYPEWRITING MACHINE

Application filed May 26, 1930. Serial No. 455,580.

This invention relates to means for winding and automatically reversing an ink-ribbon in a typewriting machine, especially a machine of the portable class, in which all mechanisms must be light, compact, simple, inexpensive, durable and not liable to get out of order.

One of the main objects of the invention is to secure certainty of ribbon-reversing action by the use of a few strong parts, the problem pertaining to ribbon-spools which are placed at opposite sides of the machine, at the front of the platen, where there is no room for ribbon winding and reversing trains.

According to the present invention, near the ends of the ribbon there are fastened buttons, and the ribbon is threaded through eyes in levers placed near the spools. Accordingly either lever may be engaged and swung by the ribbon-button, when the adjacent spool is nearly unwound.

The levers form part of a crowding train, which includes a shaft extending across the machine under the key-levers, and also includes toothed wheels on the ends of said shaft, and crowding dogs for these wheels. Said shaft is also a member of a spool-winding train, having on its ends gears to mesh with pinions, the latter fastened upon the bottom ends of vertical spool-shafts. The main or cross shaft is rotated by means of a ratchet-wheel, driven by a pawl that is operated at every key-stroke. A ribbon-winding ratchet-wheel is placed at the middle of the shaft, and said shaft is swiveled adjacent said ratchet-wheel, so that either end of the shaft may be swung or vibrated forwardly, while the other end swings rearwardly. A crowder operating at either end of the shaft, serves to re-engage the winding gears at that end, and to disengage the winding gears at the other end of the main shaft. A crowding dog at each side of the machine is normally out of engagement with an associated toothed wheel on the cross-shaft, but the button on the ribbon causes the lever to vibrate, and the latter, being connected by a link to the dog, swings the dog into mesh with its wheel. The dog being caught in the

teeth of the wheel, the rotation of the latter forces the shaft to swing under the pressure or reaction of the dog thereon, as the dog is turned by the wheel.

The invention can be successfully carried out by mounting all of the aforesaid ribbon winding and reversing mechanisms and spools upon the stationary framework of the typewriter, instead of mounting the spools upon the carriage-shift frame, as heretofore.

Thus there is only a single connection extending across the machine, and all the parts are very compact. At each side the dog-setting train includes only a ribbon-lever and a link, which are compactly placed just within the side walls of the machine. The entire ribbon-reversing mechanism includes only seven members, namely, two levers, two links, two dogs, and a shaft, the latter being part of the crowding train and also part of the winding train. The shaft is preferably provided with a worm-gear to mesh with the spool-pinion, but the invention is not limited to this particular type of gearing. The gears and wheels may all be of very small diameter, to meet the requirement of compactness. The liability of faulty action of either the winding or the reversing operation is eliminated. There are so few parts that they can all be made heavy and strong, without unduly adding to the weight of the portable typewriter. The parts are all cheaply made, and simple to manufacture and assemble.

Other features and advantages will hereinafter appear.

In the accompanying drawing, Figure 1 is a fragmentary cross-sectional view, front to rear, through an Underwood portable typewriting machine having my invention applied thereto.

Figure 2 is a fragmentary top plan view of the structure shown in Figure 1.

Figure 3 is a fragmentary perspective view of the right-hand ribbon-spool and the ribbon feeding and reversing mechanism associated therewith.

Figure 4 is an operational view illustrating the position of the crowding dog or pawl

just after the pawl has been raised to a position for engaging the ratchet-wheel.

Figure 5 is a view similar to Figure 4, the crowding pawl and ratchet-wheel being shown in position just before reversal of the ribbon-feed takes place.

My invention is illustrated as applied to an Underwood portable typewriting machine wherein types 10 strike against a platen 11 on a platen-shaft 12 journaled in a platen-carriage 13. Each type 10 is mounted on a type-bar 14, which is fulcrumed on a rod 15 and is connected by a link 16 to a bell-crank 17, which is pivoted on a rod 18 in a cross-wise bell-crank mounting bar 19. A key 20, for swinging each type against the platen, is mounted on the forward end of a key-lever 21, which is fulcrumed about a rod 22 on a main frame 23. A laterally-extending pin 24 on the lever 21 engages in a slot 25 in the bell-crank 17, and depression of the key 20 is thus made effective to swing the associated type 10 against the platen 11.

Extending under the levers 21, transversely thereto, is a universal bar 26 which has two rearwardly-extending arms 27 fastened on a rock-shaft 28, which is mounted on brackets 30 fastened to a crosswise channel-bar 31 on the main frame 23. A compression return spring 32 for each key-lever 21 rests on the bar 31. A tensile spring 33 fastened to an arm 27 and to a member (not shown) of the main frame 23 holds the universal bar 26 in its uppermost normal position, which is determined by the arm 27 abutting against a pin 34. The parts described above may be of the same construction as like parts in an Underwood portable typewriting machine.

An inked ribbon 35 is threaded through the usual ribbon-vibrator 36, which is vibrated upwardly by instrumentalities (not shown) to dispose the ribbon 35 in front of the printing point on the platen just before each type 10 strikes against the platen. The ribbon 35 is mounted on a pair of ribbon-spoils 37, one mounted at the right side of the machine and one at the left in a way to be presently described.

For feeding the ribbon 35 past the printing point as the typing proceeds, the ribbon-spoils 37 are rotatively connected to the universal-bar rock-shaft 28 by instrumentalities including an upreaching arm 39 fastened on the rock-shaft 28, adjacent a journal-member 40 mounted on the bar 31, and a drive-pawl member 41 which is loosely fastened to the upper end of the arm 39 extends forwardly and has a tooth 42 for engaging the teeth of a ratchet-wheel 43 on a crosswise drive-shaft 44.

For ribbon-reversing purposes, the drive-shaft 44 is swivelly mounted by instrumentalities including a hub 45 integral with the ratchet-wheel 43 and fastened on the shaft 65 approximately at the center line of the ma-

chine. The hub engages loosely in an oversize hole 46 in a rearwardly-extending mounting bracket 47 which has a transverse arm 48 fastened by screws 49 to the cross-bar 19. The hole 46 may be slightly flattened or chamfered, as indicated in Figure 2. The hole 46 is positioned so that when the axis of the shaft 44 substantially coincides with the axis of the hole, the shaft is disposed a short distance to the rear from a vertical plane through the centers of the spools 37. A detent or dog-pawl 50 is pivoted on a screw 51 threaded in the side of the bracket 47 in front of the ratchet-wheel 43 and extends rearwardly under the same, and a tensile spring 52, having one end fastened to the rear end of the pawl 50 and one end fastened to the drive-pawl 41, holds the dog-pawl in engagement with the ratchet-wheel 43. It can be readily seen that the drive-shaft 44 is compactly positioned below the other operating mechanism of the typewriting machine and occupies space that heretofore was not used.

For operatively connecting the two spools 37 to the drive-shaft 44, each spool is seated on a spool-head flange 55 integral with a hub 56 which is fastened by a screw 57 to a vertical shaft 58, having an upper end portion extending upwardly past the flange 55 through the usual axial bore of the spool to receive a thumb-nut 60. A usual upreaching pin 61, fast in each flange 55, engages in a usual hole in the associated spool 37, and the latter rotates with the flange.

For supporting each spool, a bracket 62 is fastened by a screw 63 to a side member 64 of the main frame and has an inreaching shelf 65 apertured for receiving with a running fit the hub 56, so that the flange 55 is seated on the shelf.

Each shaft 58 extends downwardly to a point slightly below the axis of the drive-shaft 44. An inreaching integral bracket-lug 66 of the main frame 23 is positioned a short distance above the end of the shaft 58 and is apertured for receiving the same with a running fit, the lug 66 and the shelf 65 thereby serving to hold the shaft in vertical operative position.

The operative connection of the right-hand shaft 58 to the drive-shaft 44 (see Figure 3) is described below, and it will be understood that the same description applies to the connection between the left-hand shaft 58 and the drive-shaft 44, except that the direction of the drive is opposite from the first-named connection. A gear-wheel 67 is fastened on the lower end of the shaft 58 by screws 68 threaded in a hub 69 of the gear on the shaft.

A worm 71 is mounted on the shaft 44 near each end for engaging the adjacent gear 67. The worms 71 may be fastened on the shaft by screws 72 threaded in integral hub-elements 73 of the worms.

Upon disposal of the shaft 44 in the Figure

2 position, it can be seen that by means of the above-described mechanism, depression of the keys 20 will oscillate the universal bar 26, and rotate the shaft 44 step by step, and gradually 5 wind up the ribbon 35 on the left-hand spool 37.

It is a feature of the present invention to provide compact, inexpensive, positively operating mechanism for automatically reversing 10 the feed of the ribbon 35 when it is substantially unwound from the paying-off ribbon-spool which, in this description, it will be assumed is the right-hand spool 37. The parts of the ribbon-reversing mechanism 15 described below, except as otherwise noted, are those associated with the right-hand ribbon-spool 37. Similar parts are associated with the left-hand spool 37, some of the last-named parts being reversely 20 made as regards corresponding parts associated with the right-hand spool 37. The reversing mechanism includes two usual buttons 74 fastened on the ribbon 35, one button 25 adjacent each end of the ribbon and a lever 75 having a narrow open slot 76 in an upreaching end portion 76^a through which slot the ribbon 35 is drawn as it is fed past the printing point. The slot 76 is not wide 30 enough to pass the button 74. To mount the lever 75 for having its end portion 76^a swing away from the right-hand ribbon-spool towards the printing point by the button when it comes against the lever, two integral arms 35 77 at the side of a body-portion 78 of the lever are bent toward the right-hand spool 37, and are pivotally fastened between two downreaching arms 79 of a U-shaped hanger-member 80, which may be fastened to the under side of an inturned annular flange 81 40 of a ribbon-spool cup 82 seated on the shelf 65 and fastened thereto by screws 83.

An arm 84 is integrally joined to the lower end of the body-portion 78 and extends downwardly and sidewardly, as illustrated in Figures 2 and 3. The lower end of the arm 84 is connected by a wire link 85 to an upwardly-bent ear 86 of an in-reaching lug 87 integrally joined to a "crowding" pawl 88, which is pivoted about 45 a shoulder-screw 90 threaded in the adjacent side wall 64 of the main frame 23. The screw 90 is positioned a short distance in the rear of the shaft 44 and the pawl 88 extends forwardly and slightly downwardly, 50 its forward end portion terminating in a tooth 91, as illustrated in Figure 4.

For co-operating with the crowding pawl 88, a ratchet-wheel 92 is fastened on the shaft 44 in front of the tooth 91. It will 55 be noted that the right end of the shaft 44 is disposed in the Figure 2 position away from the gear-wheel 67 when the ribbon is being unwound from the right-hand spool 37, and also the shaft 44 and the ratchet-wheel 92 are being rotated clockwise.

When the ribbon 35 is unwound from the right-hand spool 37, the button 74 swings the upper slotted end 76^a of the lever 75 over, and the forward end of the crowding pawl is lifted upwardly by the link 85 fastened to the lever 75 until the forward extremity of the pawl engages against the ratchet-wheel 92 at a point which is considerably below a horizontal plane through the axis of the ratchet-wheel (see Figure 4). Thereafter, the pawl is engaged by a tooth 93 of the ratchet-wheel and begins to "crowd" by a toggle-like action the ratchet-wheel and the right-hand end of the shaft 44 forward toward the adjacent shafts 58. The teeth 93 of the ratchet-wheel are pointed or sloped in the opposite direction to the rotation of the ratchet-wheel 92 which insures positive engagement of the tooth 91 by one of the teeth 93 after the pawl 88 is swung up against the ratchet-wheel 92 and the latter is subsequently rotated by depression of the key-levers 20.

The "crowding" of the shaft 44 moves the right-hand worm 71 toward its associated gear-wheel 67, and at the same time the left-hand worm 71 is gradually moved out of engagement with the associated gear 67.

After a small angular movement of the swiveled shaft 44, caused by action of the pawl 88, the left-hand worm 71 is disengaged, by a minute amount, from its gear 67, and the right-hand worm 71 is brought to a point wherein it is just out of engagement with its associated gear 67.

It is a feature of the present invention to provide light, simple, positive means for quickly moving the worm associated with the paying-out ribbon-spool past the above-noted just-out-of-engagement point into full engagement with its associated gear. In carrying out this feature, a thin plate-member 95 is pivotally mounted on the screw 90 and extends forwardly along the side wall 64. Two substantially semicircular notches or valleys 96 are cut in the member 95 adjacent the shaft 44. The rearmost notch 96 is positioned whereby the right-hand end portion of the shaft 44 is seated in it when the ribbon 35 is being paid off the right-hand spool 37 prior to the beginning of the above-described crowding action of the pawl 88. The other notch 96 is positioned just forward from the above-described rearmost notch, so that a pointed hill-like element 97 is left between the notches. As the crowding pawl 88 begins to move the shaft 44 angularly, the latter rides up on the hill-element 97 and is shortly disposed in the Figure 4 position, the notched plate-member 95 being cammed down against the tension of a return spring 98, since the shaft 44 is held against upward movement by having its end portion extend

125
130

outwardly from the notch-member 95 and engage against the lower edge 99 of an adjacent portion of the side wall 64. A further small crowding action of the pawl 88 moves the center of the shaft 44 forward past the rear edge of the foremost notch 96, and the latter then becomes effective through the power of the spring 98 to cam the right-hand end of the shaft 44 forward to be seated in the foremost notch and the right-hand worm 71 fully engages the associated gear 67. At the same time the left-hand end of the shaft 44 is swung rearwardly to be seated in its associated rearmost notch 96. It can be seen that other devices, such as miter gears, can be substituted for the worm-and-gear elements of my ribbon-feed-reversing mechanism without departing from the scope of my invention.

Provision of the two notches 96 not only expedites the final action of the ribbon-reversing mechanism and effects a quick reversal of the ribbon-feed, but the notches also serve as detents to hold one worm 71 positively in engagement with its associated gear while the other worm is held positively out of engagement with its associated gear. Furthermore the action of the foremost notch 96, which cams the shaft 44 angularly a considerable amount, moves the ratchet-wheel 92 entirely clear of the pawl 88, whereby the latter is free to be returned to normal position by a spring 100, which has one end fastened to the pawl 88 and the other end to the forward extremity of an inreaching integral shelf 101 of the side wall 64 which supports the one end of the channel-bar member 31. The downward movement of the notched member 95 is limited by a rearwardly-extending stop-finger 103 engaging a pin 104 fastened in the side wall 64.

It is another feature of the present invention to provide means which are effective for conveniently reversing, at will, the feed of the ribbon 35 and also for manually winding up the ribbon on either spool. To this end, the right-hand end portion of the shaft 44 extends past the adjacent side wall 64 and through a cut-out section 105 of a usual outer decorative frame 106, and has a knurled thumb-piece 107 fastened on its outer end by a screw 108. To manually reverse the feed of the ribbon 35, it is only necessary to move the thumb-piece 107 forward or rearward. To manually feed the ribbon 35, it is only necessary to rotate the thumb-piece 107. It will be noted that a thumb-piece is not provided on the left-hand end of the shaft 44, since such a thumb-piece is not needed except on one end. With the exception of the thumb-piece, the parts of the ribbon-reversing mechanism associated with the left-hand end of the shaft 44 will be the equivalent of the parts described above for the right-hand end, and will operate in a similar man-

ner. It will be understood, of course, that some of the parts associated with the left-hand end of the shaft 44 are reversely made relative to the parts of the right-hand end, and will move accordingly in performing their functions.

Variations may be resorted to within the scope of the invention, and portions of the improvements may be used without others.

Having thus described my invention, I claim:

1. In a typewriting machine, the combination of type-operating keys, ribbon-spools, a gear-wheel connected to each spool, a worm connectible to each of said gear-wheels, a single drive shaft carrying one of said worms on each end, a swiveled mounting for said drive shaft, whereby, upon engagement of one of said worms with its associated gear-wheel, the other worm is swung out of engagement with its associated gear-wheel, crowding instrumentalities dependent upon the rotation of the drive shaft for engaging either worm with its associated gear-wheel, said instrumentalities including a ratchet-wheel on each end of said shaft and a normally idle crowding pawl for each ratchet-wheel, and means operable by unwinding movement of said ribbon for moving either of said pawls into engagement with its associated ratchet-wheel, to co-operate therewith to enable the shaft by its rotation to crowd itself to make a swinging movement upon its swiveled mounting, to cause the ribbon to become rewound upon the empty spool.

2. In a ribbon-spool reversing mechanism for a typewriting machine, the combination with a pair of ribbon-spool-shafts, of a swiveled driving shaft extending between said spool-shafts and movable to be connected with either of them, a pair of normally idle crowding devices for moving said shaft about its swiveled mounting alternately in opposite directions, each device including a toothed wheel on an end of said swiveled shaft, a pawl having a fixed pivot and a lever-system actuated by the ribbon of said mechanism for moving said pawl to engage said wheel, whereby said crowding devices become alternately effective, and instrumentalities for disabling the crowding device then moving said drive-shaft, said instrumentalities returning said device to normal position, and thereafter effective to move said drive-shaft an additional amount for connecting it with the paying-off spool-shaft, whereupon it becomes the winding-up spool-shaft.

3. In a ribbon-spool reversing mechanism for a typewriting machine, the combination with a pair of ribbon-spool-shafts, of a swiveled driving shaft extending between said spool-shafts and movable to be connected with either of them, a pair of normally

- idle crowding devices for moving said shaft about its swiveled mounting alternately in opposite directions, each device including a toothed wheel on an end of said shaft, a pawl having a fixed pivot and a lever-system actuated by the ribbon of said mechanism for moving said pawl to engage said wheel, whereby said crowding devices become alternately effective, and instrumentalities effective for expediting the last part of the movement of said drive-shaft in either direction and connecting it with one of said ribbon-spool-shafts, whereby quick reversal of the feed of said ribbon is secured.
5. In a typewriting machine, the combination with a pair of ribbon-spool shafts, of a driving cross-shaft having means at its ends to gear to the ribbon-spool shafts, said cross-shaft swiveled at its middle to swing either end into working position, toothed members upon the ends of said drive shaft, and ribbon-operated pawls, either of which may be moved by the unwinding movement of the ribbon into engagement with its associated toothed member, to enable the rotation of said shaft to crowd it into a swinging action about its swivel mounting, to throw one end out of engagement with the shaft of the full spool and the other end into engagement with the shaft of the empty spool, the teeth of said toothed member pointing oppositely from the direction of its rotation, for engaging and lifting the free end of the pawl while the rotation of the shaft crowds the toothed member to swing it away from the pawl.
6. In a typewriting machine, the combination with a pair of ribbon-spool shafts, of a driving cross-shaft having means at its ends to gear to the ribbon-spool shafts, said cross-shaft swiveled at its middle to swing either end into working position, toothed members upon the ends of said drive shaft, and ribbon-operable lever adjacent to each spool, a link extending from said lever, a pawl swung by said link into mesh with the adjacent toothed member on said drive shaft, to enable the rotation of said shaft to crowd it into a swinging action about its swivel mounting, to throw one end out of engagement with the shaft of the full spool and the other end into engagement with the shaft of the empty spool, and a spring to return to normal position said pawl, link and lever.
7. In a typewriting machine, the combination with a pair of ribbon-spool shafts, of a driving cross-shaft having means at its ends to gear to the ribbon-spool shafts, said cross-shaft swiveled at its middle to swing either end into working position, toothed members upon the ends of said drive shaft, and ribbon-operated pawls, either of which may be moved by the unwinding movement of the ribbon into engagement with its associated toothed member, to enable the rotation of said shaft to crowd it into a swinging action about its swivel mounting, to throw one end out of engagement with the shaft of the full spool and the other end into engagement with the shaft of the empty spool, yielding means being co-operative with said swiveled drive shaft to complete its swinging motion into engagement with the empty spool-shaft and away from the pawl.
8. In a typewriting machine, the combination with a pair of ribbon-spool shafts, of a driving cross-shaft having means at its ends to gear to the ribbon-spool shafts, said cross-shaft swiveled at its middle to swing either end into working position, toothed members upon the ends of said drive shaft, and ribbon-operated pawls, either of which may be moved by the unwinding movement of the ribbon into engagement with its associated toothed member, to enable the rotation of said shaft to crowd it into a swinging action about its swivel mounting, to throw one end out of engagement with the shaft of the full spool and the other end into engagement with the shaft of the empty spool, the teeth of said toothed member pointing oppositely from the direction of its rotation, for engaging and lifting the free end of the pawl while the rotation of the shaft crowds the toothed member to swing it away from the pawl.
9. In a typewriting machine, the combination with a pair of ribbon-spool shafts, of a driving cross-shaft having means at its ends to gear to the ribbon-spool shafts, said cross-shaft swiveled at its middle to swing either end into working position, toothed members upon the ends of said drive shaft, and ribbon-operated pawls, either of which may be moved by the unwinding movement of the ribbon into engagement with its associated toothed member, to enable the rotation of said shaft to crowd it into a swinging action about its swivel mounting, to throw one end out of engagement with the shaft of the full spool and the other end into engagement with the shaft of the empty spool, the teeth of said toothed member pointing oppositely from the direction of its rotation, for engaging and lifting the free end of the pawl while the rotation of the shaft crowds the toothed member to swing it away from the pawl, and yielding means for moving said toothed member and shaft away from the pawl an additional amount, to free the shaft from the pawl and to swing the shaft into engagement with the empty spool-shaft.
10. In a typewriting machine, the combination with a pair of ribbon-spool shafts, of a driving cross-shaft having means at its ends to gear to the ribbon-spool shafts, said cross-shaft swiveled at its middle to swing either end into working position, toothed members upon the ends of said drive shaft, and ribbon-operated pawls, either of which may be moved by the unwinding movement of the ribbon into engagement with its associated toothed member, to enable the rotation of said shaft to crowd it into a swinging action about its swivel mounting, to throw one end out of engagement with the shaft of the full spool and the other end into engagement with the shaft of the empty spool, yielding means being co-operative with said swiveled drive shaft to complete its swinging motion into engagement with the empty spool-shaft and away from the pawl.

spool and the other end into engagement with the shaft of the empty spool, one end of said shaft being extended to project beyond the machine-frame, and having a knurl upon said projection for winding the shaft and swinging it upon its swivel.
